UNITED STATES PATENT OFFICE.

WINFRED T. POWELL, OF CHICAGO, ILLINOIS, ASSIGNOR TO AUTOMATIC ELECTRIC COMPANY, OF CHICAGO, ILLINOIS, A CORPORATION OF ILLINOIS.

TELEPHONE-EXCHANGE SYSTEM.

1,308,553.

Specification of Letters Patent.

Patented July 1, 1919.

Application filed July 24, 1916. Serial No. 110,925.

To all whom it may concern:

Be it known that I, WINFRED T. POWELL, a citizen of the United States of America, and a resident of Chicago, county of Cook, 5 and State of Illinois, have invented certain new and useful Improvements in Telephone-Exchange Systems, of which the following is a specification.

My invention relates in general to improvements in telephone exchange systems and is concerned more particularly with those systems in which the telephonic connections are established through the medium of automatic selector and connector switches.

15 Systems of the foregoing character are naturally divisible into two great classes, automatic and semi-automatic, the distinction lying in the method of controlling the automatic switches. In the so-called full 20 automatic systems each substation instrument is provided with an impulse sender or calling device by means of which the subscriber is enabled to control the central office switching mechanisms to establish connections entirely independent of manual assistance at the exchange. On the other hand, in 25 semi-automatic systems, the substation instruments are of the ordinary manual type, and a subscriber, when making a call, is first 30 connected with an operator, who controls the automatic switches thereafter to establish the connection in accordance with directions supplied by the calling subscriber.

It is the chief object of my invention to 35 provide a telephone exchange system in which it is a matter of indifference whether any particular substation is provided with a calling device or not. In my improved system, a calling line, whether manual or automatic, is connected by a preliminary trunking operation responsive to the removal of the receiver with the first of the numerical selector switches through the medium of which the connection is to be established. 40 Immediately afterward, if the calling line is equipped with a manual substation only, the call is trunked to an operator who controls the automatic switches to establish the connection in the well known manner. In case, 45 however, the calling line is equipped with an automatic substation, the latter trunking operation is not performed and the calling subscriber himself controls the establishment of his connection. To accomplish the 50 foregoing, apparatus is provided associated

with the preliminary trunking equipment which is able to discriminate between automatic and manual calling lines, as will be fully explained hereinafter.

A further feature of my invention relates 60 to the preliminary trunking apparatus. Primary and secondary finder switches are employed which mechanically are of the well known single rotary type but whose circuits are modified in certain details which 65 will be explained, with a view to securing great rapidity in extending a calling line to an idle selector switch.

Still another feature of my invention relates to a combined line and cut-off relay. 70 By a peculiar circuit arrangement and relay construction I am able to dispense with the usual line and cut-off relays and provide instead a single relay individual to each line 75 which performs the functions of both a line and a cut-off relay.

These and other features will be explained more in detail in the description which is to follow, reference being had to the accompanying drawings. For a clear understanding of the drawings Figures 1, 2, and 3 should be arranged in order with the lines thereof in alinement, and Fig. 4 should be placed beneath Fig. 3 with the lines at the 80 top of Fig. 4 in alinement with the lines at the bottom of Fig. 3. When properly arranged the drawings show diagrammatically the essential parts of a complete system embodying the principles of my invention.

It has been thought advisable to show a 85 portion of the apparatus in operated position whereby a connection has been established between a calling manual substation A (Fig. 1) and a called automatic substation A² (Fig. 3). The said connection has been 90 established through the medium of the primary and secondary finder switches C and D, the selector switch E (Fig. 2), and the connector switch F (Fig. 3). The operator's equipment by means of which the establishment of the connection was controlled is shown in the lower half of Fig. 3 and in Fig. 4, while the means by which the call was extended to the operator's position comprises the relay equipment H and the primary and secondary line switches M and N (Fig. 2). In Fig. 5 is shown in detail the spring combination of one of the subscribers' individual 105 line relays.

Referring now to Fig. 1, the manual sub- 110

station A comprises the usual common battery arrangement in which the transmitter and receiver are connected in series. The line conductors 12 and 13 have allotted to them at the exchange a combined line and cut-off relay 14; sets of multiple contacts in the banks of a plurality of finder switches, one of which sets is indicated by reference characters 27-30, inclusive; and a set of 10 multiple contacts (not shown) in the bank of each connector, such as connector F (Fig. 3), which has access to the group of lines of which the line of substation A is one. The normal conductors 35, 36, and 37 extend 15 to these latter sets of contacts.

The relay 14 comprises two windings one of which, the winding 15, is of high resistance and few turns, being preferably of German silver wire. Referring to the detailed showing of Fig. 5, when the two windings are energized in series the armature is attracted with sufficient force to bring the contact spring 21 against the bushing by which the springs 17 and 19 are controlled 20 thereby separating the said spring 21 from spring 22. The springs 17 and 19, however, are quite stiff and consequently are not separated from their resting contacts 18 and 20. When the winding 16 is energized alone the 25 armature is fully attracted.

It has been mentioned before that the subscribers' lines may be equipped either with manual or automatic substations indiscriminately and there is shown, accordingly, an 30 automatic substation A' provided with line conductors 12' and 13' which terminate at the exchange in individual line equipment exactly like that already described in the case of the line of substation A. Being an 35 automatic substation, the substation A' is provided with the usual calling device or impulse sender which as shown herein diagrammatically comprises a pair of impulse springs 2 and 3 controlled by the impulse 40 wheel 4 through the medium of a finger hole dial (not shown). An impulse sender suitable for the purpose is shown in British patent to S. G. S. Dicker, #29,654 of 1910.

For calling purposes the subscribers' lines 45 are preferably divided into hundred line groups, corresponding to the capacity of a connector switch. Each group of lines is served by a group of selector switches, usually ten in number, one of these selectors 50 being shown at E (Fig. 2). As is customary in finder switch systems, each selector switch is provided with a primary finder switch by which it may be connected with a calling line. For example, the selector switch E is 55 provided with the primary finder switch C. In order to decrease the maximum number of contacts over which a primary finder may be required to hunt to locate a calling line, I do not give these primary finders direct 60 access to calling lines but instead interpose

lesser groups of secondary finder switches, one of which switches is indicated by reference character D. In carrying out this plan, a hundred line group may be sub-divided 65 into four twenty-five line groups, the lines 70 of each sub-group being served by six secondary finder switches. The secondary finders of the four sub-groups, twenty-four altogether, are accessible to the ten primary 75 finder switches corresponding to the ten selector switches serving the main group. By the foregoing arrangement, each finder switch is required to hunt over a maximum of twenty-five lines (twenty-four in the case of the primary finders) instead of one hundred lines, as would be the case if primary 80 finders alone were used.

Mechanically the finder switches shown herein are of the well known single rotary type in which the wipers have no normal 85 position. A switch of suitable mechanical construction is shown in the patent to Clement, #1,107,153. The circuits by which the finder switches are controlled, however, are believed to be new in certain details 90 which will be fully described in the detailed specification which is to follow.

The selector switch E (Fig. 2) is of the general type of selector switch disclosed in U. S. Letters Patent #815,321, granted 95 March 13, 1906, to Keith, Erickson, and Erickson; the side switch and private magnet, however, being omitted and the circuits being modified to enable the switch to operate in a system in which the impulses are 100 delivered over the two sides of the line in series. A selector switch of the foregoing type, as is well known, may be operated in response to the first digit of a called number 105 to select one of a number of main groups into which the lines of the exchange are divided. For this purpose the selector E, in common with other similar selectors, may be given access to a number of groups of trunk lines, the trunk lines of each group being 110 extended to a group of connector switches.

One of these trunk lines is shown extending to the connector F (Fig. 3), which is of the general type of connector switch disclosed in U. S. Letters Patent #815,176, 115 granted March 13, 1906, to Keith, Erickson, and Erickson; being, however, of the particular type disclosed in U. S. Letters Patent #13,901, reissued April 13, 1915, to Frank Newforth. A connector switch of the foregoing type may be given access to a group 120 of one hundred subscriber's lines as has been previously mentioned, and is operable in response to the two last digits of a called number to establish connection with any line 125 in the group.

One of the lines to which the connector F has access is shown extending to the substation A' which is similar to the substation A' already described, and is provided with simi- 130

lar individual line equipment at the exchange.

Before proceeding further it should be mentioned that while I have shown the first selector switch E as having direct access to the connector switches, this will be true only in a small exchange. In larger systems second and third selectors may be interposed in the usual and well understood manner.

Referring now to Fig. 2 again, the apparatus indicated collectively by reference character H comprise a group of three relays individual to the trunk extending to the selector E and whose function it is to determine whether a calling line is automatic or manual. In the latter case the apparatus H operates to direct the call to an operator's position. Since the apparatus H must be able to discriminate between automatic and manual lines it is evident that the two kinds of line must have some distinguishing feature. With this object in view each individual line relay is provided with two terminals, indicated in the case of line relay 14 (Fig. 1) by reference characters 24 and 25, between which there is or is not connected a resistance, such as resistance 26, depending on whether the associated line is equipped with a manual or automatic substation. The effect of this resistance in controlling the operation of the relays H will be fully explained hereinafter.

It may happen that certain groups of lines may be equipped throughout with automatic substations in which case the apparatus H associated with those groups may be dispensed with. For convenience I have contemplated mounting each group of relays H on a bracket provided with spring clip terminals which, when the equipment is installed, will engage corresponding spring clips or jacks 123-128, inclusive. When the relay equipments associated with a certain group of lines are to be removed, it is only necessary to dismount the several relay brackets, and connect the terminals 123, 124, and 125, respectively, with the terminals 126, 127, and 128, by means of jumpers. This feature is especially valuable where an existing manual or semi-automatic system is to be gradually changed over to a full automatic system.

The primary and secondary rotary line switches M and N are of the same general construction mechanically as are the finder switches C and D already described, although the circuits are simplified and changed in certain details which will be explained in order to take care of the somewhat different functions which these switches perform.

The trunking arrangement of the primary and secondary line switches is in accordance with the usual practice. A plurality

of primary line switches similar to the line switch M are given common access to a group of twenty-five secondary line switches similar to the line switch N. The secondary line switches have common access to a group of twenty-five trunks which extend to operators' positions. One of these is shown extending from the bank contacts 194-197, inclusive, to the operator's equipment indicated collectively by reference character O (Fig. 3). It is considered best to have three trunks terminate in each operator's position, although the number may be varied if desired. Means is provided whereby when a call is received over one trunk the others terminating in the same position are made busy until after the call is handled by the operator. An individual busy key K is also provided.

In Fig. 4 there is shown an operator's impulse sending equipment which is individual to the trunk line terminating in the equipment O (Fig. 3). The equipment shown in Fig. 4 is taken from the co-pending application of John G. Blessing, Serial #740,953 and consequently no detailed description will be given herein. It will suffice to say here that upon receiving a call the operator depresses in rapid succession the keys which correspond to the digits in the desired number, after which she depresses the starting button S. When the operator depresses the digit keys the sender automatically registers the number wanted and thereafter, in response to the operation of the starting button, proceeds to transmit to the automatic switches the required series of impulses to control the establishment of the connection, all of which will appear more clearly from the description of the operation which will presently be given.

While I have shown throughout the drawings a plurality of batteries it is to be understood that there is preferably but one battery having its positive pole grounded. The auxiliary apparatus shown in association with the connector F (Fig. 3) and comprising the ringing current generator Gen, the interrupter I, and the busy signaling machine Q, are of the usual type and perform the same functions as the same named pieces of apparatus in other automatic exchanges.

Having briefly described the apparatus, I will now proceed to a description of the operation thereof. For the purposes of this explanation it will be assumed that the subscriber at the manual substation A (Fig. 1) wishes to obtain connection with the subscriber at the automatic substation A' (Fig. 3) this being the complete circuit connection shown in the drawings. Afterward it will be explained wherein the operation of the equipment differs when the subscriber at the automatic substation A' (Fig. 1) attempts to establish the same connection. A great part

of the apparatus shown being well known, having been fully described in the publications referred to, the operation will be described in a more or less general manner, the details being given only when they have to do with the principles of my invention.

Referring now to Fig. 1, when the subscriber at substation A removes his receiver to initiate the call a circuit is completed for the individual line relay 14 and the sub-group starting relay 39 which may be traced as follows: ground at G², winding of relay 39, armature 17 of relay 14, contact 18, line conductor 12, to and through substation A, line conductor 13, contact 20, armature 19 of relay 14, and windings 15 and 16 of relay 14 in series to battery B². Upon the closure of the above circuit, relay 14 attracts its armature sufficiently to separate the spring represented by armature 21 from its resting contact 22, the other springs being unaffected. This operation results in the removal of ground G² from the multiple test contacts, one of which is test contact 28, in the banks of the group of secondary finders serving the sub-group of lines of which the line of substation A is one.

The sub-group starting relay 39, upon energizing, connects ground G² to the starting wire 43 which extends to the first secondary finder switch of the associated sub-group; and also connects the same ground to the starting wire 45 which is common to the starting relays of all four sub-groups and which extends to the first primary finder switch of the main group. It is understood that finder switches C and D are for convenience shown as being the first switches in their respective groups.

In the description of the operation of the finder switches which is to follow it will be assumed that the wipers of secondary finder switch D are resting on some line other than the line of substation A and that the wipers of primary finder switch C are resting on the contacts of some secondary switch other than the finder switch D, whence it appears that both finder switches will be required to rotate in order to complete the connection. It should be remembered also that the test contacts, similar to test contact 28, of all non-calling lines are connected to ground, as are also the test contacts, similar to test contact 96, of all non-hunting secondary switches.

By the grounding of the starting wire 43, a circuit is completed by way of the back contact of armature 66 of relay 50 and the winding of relay 51 of the secondary finder switch D to battery B². Upon energizing the line relay 51 disconnects ground G² from test contact 96 by means of its armature 59; connects by means of its armature 55 the common conductor 60 to the lower terminal of line switching relay 50; and lastly completes an operating circuit for the rotary

magnet 52 over the following path: ground on test contacts similar to test contact 28, wiper 32, armature 61 of relay 50, contact 62, contact 54, armature 53 of relay 51, armature 71 of rotary magnet 52 and its back contact, and winding of rotary magnet 52 to battery B². Since the rotary magnet 52 interrupts its own circuit by means of its armature 71 it will operate in the manner of a buzzer to advance the wipers 31-34, 75 inclusive, step by step in search of the set of contacts 27-30, inclusive, of the calling line. During the rotation, the rotary magnet 52 at each energization, substitutes for its own winding the common conductor 70 extending to the slow-acting relay 105. Relay 105 attracts its armature at the first impulse and retains it while the finder switch D is operating.

Proceeding now to a consideration of the primary finder switch C, upon the grounding of the starting wire 45, a circuit is completed by way of the back contact of armature 86 of relay 75 and the winding of line relay 76 to battery B². Upon energizing, relay 76 connects by means of its armature 82 the common conductor 85 to the lower terminal of relay 75, and also completes an operating circuit for the rotary magnet 77 over the following path: ground on test contacts similar to test contact 96, wiper 102, armature 78, contact 79, contact 88, armature 84 of relay 75, armature 83 of rotary magnet 77 and its back contact, and the widening of rotary magnet 77 to battery B². Since the rotary magnet 77 interrupts its own circuit by means of its armature 83, it will operate in the manner of a buzzer to advance the wipers 101-104, inclusive, step by step in search of the set of contacts 95-98, inclusive, of the secondary finder switch D. During the rotation the rotary magnet 77 maintains the slow-acting relay 106 actuated by way of the common conductor 87 in the same way as was described in the case of the relay 105 and the rotary magnet 52 of the secondary finder switch.

It will be seen that the primary and secondary finder switches are started simultaneously. The secondary finder switch continues to rotate its wipers until the test wiper 32 arrives at the ungrounded test contact 28 of the calling line. Likewise, the primary finder switch continues to rotate its wipers until the test wiper 102 arrives at the test contact 96 of the hunting secondary finder switch. Both finder switches having ceased to rotate, current for the energization of line switching relay 50 of finder switch D will flow over the following path: ground at G², armature 109 of relay 106, contact 110, common conductor 60, armature 55 of relay 51 and its front contact, winding of relay 50, armature 71 of rotary magnet 52 and its back contact, and winding of rotary mag-

net 52 to battery B^3 . Relay 50 is of high resistance so that the rotary magnet 52 is not affected. Upon energizing, relay 50 shifts its contact springs to the position shown with 5 the result that the wiper 32 is disconnected by means of armature 61 from the circuit extending to the rotary magnet; a circuit for the cut-off relay 14 is prepared at armature 65; and the starting wire 43 is disconnected by means of armature 66 from the line relay 51 and, upon the deenergization of the line relay, is connected to the starting wire 44 of the next finder switch. At the same time that relay 50 is operated, the line 10 switching relay 75 of the finder switch C is energized over the following circuit: ground at G^5 , armature 107 of relay 105, contact 108, common conductor 85, armature 82 of relay 76 and its front contact, winding of relay 75, armature 83 of rotary magnet 77 and its 15 back contact, and winding of rotary magnet 77 to battery B^4 . Relay 75, like relay 50, is of high resistance. Upon energizing, relay 75 disconnects the wiper 102 from the operating circuit extending to the rotary magnet 77 by means of armature 84; disconnects the starting wire 45 from the line relay 76 and, upon the deenergization of the line relay, connects it to the starting wire 46 20 of the next finder switch; prepares a holding circuit for itself by means of its armature 90; and by means of armatures 92 and 93 extends the wipers 101 and 104 to the double-wound line relay 300 of the selector E. 25 The said line relay 300 is now energized over the following circuit: ground at G^7 , lower winding of line relay 300, normally closed contact of relay 302, terminal 127, conductor 154, resting contact and armature 133 of relay 130, terminal 124, conductor 121, contact 93, wiper 104, bank contact 98, wiper 34, bank contact 30, line conductor 12, to and through substation A, line conductor 13, bank contact 27, wiper 31, bank 30 contact 95, wiper 101, armature 92, contact 91, conductor 120, terminal 123, armature 134 of relay 130 and resting contact, conductor 153, terminal 126, normally closed contact of relay 302, and upper winding of line relay 300 to battery B^7 . Upon attracting its armature, the line relay 300 closes a circuit for the slow-acting relay 301, which relay, upon energizing, prepares a circuit for the vertical magnet 304 in the usual 35 manner. An additional result is the closure of a holding circuit for the relays 75 and 50 of the finder switches C and D and the cut-off relay 14 which may be traced as follows: ground at G^8 , contact 308, armature 309, terminal 128, conductor 155, winding of relay 130, terminal 125, conductor 122, wiper 103, bank contact 97, contact 64, armature 65 of relay 50, wiper 33, bank contact 29, terminal 24, and winding 16 of cut-off relay 14 to battery B' . It will be seen that a

branch of the above circuit extends by way of the winding of relay 75 and the rotary magnet 77 to battery B^4 , while a second branch extends by way of the winding of relay 50 and the rotary magnet 52 to battery B^3 . The line relays 51 and 76 are made slow-acting so as to retain their armatures until after the holding circuit above traced has been completed.

Upon the completion of the holding circuit the cut-off relay 14 fully attracts its armature thereby disconnecting the line conductors 12 and 13, respectively, from the starting relay 39 and from the winding 15; and also again connecting ground G^3 to the test contact 28 to protect the line against seizure by another finder switch. The finder switch D is protected in a similar way against seizure by another primary finder switch by the connection of ground G^4 with test contact 96 upon the deenergization of line relay 51. A third branch of the holding circuit extends via conductor 35 to multiple test contacts in the banks of the connector switches which have access to the line of substation A. The relay 130 (Fig. 2) is of very low resistance so that these test contacts are brought sufficiently near to ground potential to render the said line busy.

To sum up the preliminary trunking operation briefly, it will be seen that upon the initiation of a call a primary finder switch and a secondary finder switch are started simultaneously. It will be seen further that the first switch to locate the contact set for which it is hunting waits until the other finder has stopped, when the switching relays of both finders pull up together. It is understood, of course, that in case one of the finder switches already has its wipers in engagement with the contact set to be connected with, no rotation of its wipers will take place.

The foregoing operations, resulting in the extension of the calling line to the selector E, have taken place in response to the removal of the receiver at substation A. Since substation A is a manual substation it will now be necessary to trunk the call to an operator. This operation, as has been previously mentioned, is started or controlled by the apparatus II (Fig. 2). The switching relays 75 and 50 of the finder switches C and D and the winding 16 of cut-off relay 14 being all of high resistance, they would not permit sufficient current to flow over the holding circuit to energize the low resistance relay 130 of the relay group II were it not for further provisions. The object of the resistance 26 across the terminals 24 and 25 of the cut-off relay 14 now becomes apparent. The operation of the relay 130 depends on the provision or omission of this resistance, or in other words, relay 130 is a marginal relay which operates

ates only when the calling line is one equipped with a manual substation.

It follows, therefore, that in the present case immediately upon the completion of the holding circuit the relay 130 in series therewith is energized, with the following results: By the engagement of armatures 137 and 138 with springs 139 and 140, respectively, the line conductors 153 and 154 extending to the selector E are short-circuited, the loop being closed by way of armature 143 of relay 131 and its resting contact, conductor 141, and the resting contact and armature 142 of relay 131. By the engagement of armatures 135 and 136 with springs 133 and 134, respectively, the incoming line conductors 120 and 121 are disconnected from the line conductors 153 and 154 extending to selector E and are connected, respectively, to the line conductors 150 and 151 extending to the primary rotary line switch M.

Following the energization of relay 130, therefore, the line relay 160 of the primary line switch M is energized over a circuit which may be traced as follows: ground at G², resting contact and armature 164 of relay 161, conductor 151, armature 144 and resting contact, armature 135, spring 133, terminal 124, conductor 121, previously traced circuit to and through substation A, conductor 120, terminal 123, spring 134, armature 136, resting contact and armature 145, conductor 150, armature 163 of relay 161 and its resting contact, and the winding of relay 160 to battery B². By attracting its armature 167, relay 160 completes a circuit for the switching relay 161 which extends from ground G¹⁰ by way of the said armature 167 and its working contact, winding of relay 161, armature 169 of the rotary magnet 162 and its resting contact, and the winding of the rotary magnet 162 to battery B². At the same time or an instant before the private or test wiper 171 is connected to the above circuit at a point between the relay 161 and the rotary magnet 162 by means of armature 168. The operation now depends on whether or not the test contact with which the private wiper is in engagement is busy. If this test contact is busy it will have ground potential on it and the line switching relay will be short-circuited in an obvious manner. At the same time the rotary magnet, being supplied with direct ground via the private wiper and busy test contacts, will begin operating to rotate the wipers 170-173, inclusive, step by step in search of a trunk extending to an idle secondary line switch. As soon as the test wiper 171 arrives at an idle or ungrounded test contact, assumed to be in this case the test contact 175, the rotary magnet not being able to pull up in series with the high resistance relay 161, will cease operating and the wipers 170-173, inclusive, will be brought to rest in engage-

ment, respectively, with contacts 174-177, inclusive. Also the line switching relay 161, being no longer short-circuited, will energize with the following results: By the attraction of armature 166 the private wiper 171 is shifted to the ground side of the relay 161; armature 165 connects conductor 152 to the wiper 172; and finally by means of armatures 163 and 164 the line conductors 150 and 151 are disconnected, respectively, from the line relay 160 and from ground G², and are extended by way of wipers 170 and 173, and bank contacts 174 and 177 to the line relay 186 of the secondary switch N and to ground G¹¹. The line relay 186 is now energized over the previously described circuit including the subscriber's loop and performs the same functions as have been described in the case of the line relay 160 of the primary switch M. A branch of the energizing circuit of relay 185 extends from wire junction 184 by way of test contact 175, test wiper 171, armature 166 and working contact, winding of line switching relay 161, armature of rotary magnet 162 and the winding of the said rotary magnet to battery B². The above holding circuit is established before the slow-acting line relay 160 de-energizes.

To proceed, upon the energization of its line relay 186, the secondary switch N is operated in the same manner as was the primary switch M, whereby connection is extended through the medium of the switching relay 185 and the wipers 190-193, inclusive, to an idle trunk terminating in an operator's position, assumed to be in this case the trunk line represented by bank contacts 194-197, inclusive. The trunk conductors 201 and 202 extend by way of normally closed contacts of relay 207 to the double-wound relay 205, which relay is now energized over the subscriber's loop to complete a holding circuit for the primary and secondary line switches M and N which may be traced as follows: ground at G¹², armature 210 and working contact, normally closed contact of key K, conductor 203, test contact 195, private wiper 191, and armature 183 and its working contact to wire junction 184, where the circuit divides, one branch supplying ground to the line switching relay 185 to maintain it energized, while the other branch is the same as the previously described holding circuit of switching relay 161. It will be observed that from wire junction 213 a branch of the above holding circuit extends to armature 212^a of relay 207. The back contact of armature 212^a is connected in multiple with the back contacts of corresponding armatures 212^b and 212^c of the other two trunks terminating in the same position, thereby rendering these trunks busy.

When the double-wound relay 205 is energized, as has been described, a circuit is 130

completed from ground G^{14} for lighting the signal lamp L , whereby the operator is informed that a call has been received. The operator will now operate momentarily the key K' , associated with the lamp L , thereby completing in an obvious manner an energizing circuit for the relay 209. Upon energizing, the relay 209 locks itself to ground G^{15} (Fig. 4) by way of conductor 214, extinguishes the lamp signal L , and extends the line conductors 201 and 202 to the operator's telephone set.

The calling subscriber is now connected with the operator, to whom he repeats the telephone number of the subscriber at substation A^2 . Upon learning the desired number the operator depresses in rapid succession the corresponding digit keys, shown at the right of Fig. 4, of the impulse transmitter associated with the trunk over which the call was received, and then depresses the starting button S of that impulse transmitter. The operator pays no further attention to the call after performing these operations.

In response to the actuation of the digit keys certain ones of a plurality of levers (not shown) arranged radially on the wheel 231 are set by means of an arm (also not shown) operated by the magnet 227 and controlled by the solenoids 228. At the same time the lamp L' is lighted by the closure of contact springs 240, which are controlled mechanically by the operation of any one of the digit keys and which lock in operated position. In this way the required number is registered on the wheel 231. The lamp L' indicates that the register is in set or partially set position but is not operating to transmit impulses.

Upon the operation of the starting button S the contact springs 240 are unlocked, thereby breaking the circuit of the lamp L' , and at the same time a circuit is completed for the relay 225 which relay is accordingly energized with important results which will now be described. By the removal of ground G^{15} from conductor 214, the relay 209 is de-energized to disconnect the operator's head set. By the connection of ground G^{15} to the conductor 215 a circuit is completed for relay 206. Upon energizing, relay 206 connects ground G^{16} to the holding trunk conductor 203, in order to maintain the holding circuit closed independent of the relay 205, and at the same time closes a circuit from the same ground G^{16} to the relay 207. Relay 207, upon energizing, disconnects the holding trunk conductor 203 from its multiple connection to armatures 212^b and 212^c, whereby the other two trunks terminating in the same position are again placed in idle condition. As a further result of the energization of relay 207, a circuit is completed for the relay 131 of the relay group

H , which may be traced as follows: ground at G^{15} , conductor 215, lower armature and contact of relay 206, lower armature and contact of relay 207, winding of relay 208, conductor 204, bank contact 196, wiper 192, 70 lower armature and contact of relay 185, bank contact 176, wiper 172, lower armature and contact of relay 161, conductor 152, and winding of relay 131 to battery B^{12} . Relay 208 included in the above circuit, operates 75 the register R to count the call. Relay 131, upon energizing, completes the control circuit for the automatic selector switch E which has already been prepared by the relay 207 and which may be traced as follows: 80 ground at G^7 , lower winding of line relay 300, normally closed contact of relay 302, terminal 127, conductor 154, spring 139 and armature 137 of relay 130, spring 142 and armature 144 of relay 131, conductor 151, 85 primary and secondary line switches M and N to conductor 202, inner lower armature and contact of relay 207, conductor 217, impulse springs 236, conductor 216, inner upper armature and contact of relay 207, conductor 201, secondary and primary line switches N and M , conductor 150, armature 145 and spring 143 of relay 131, armature 138 and spring 140 of relay 130, conductor 153, terminal 126, normally closed contact of 95 relay 302, and the upper winding of line relay 300 to battery B^7 . More briefly described, the operation of relay 131 results in the substitution for the short-circuiting conductor 141 of the loop extending back 100 through the primary and secondary line switches M and N and the contacts of the relay 207 to the impulse springs of the operator's impulse sender. This operation, therefore, places the selector E under the 105 control of the said impulse springs.

A further result of the operation of relay 131 which should be mentioned at this time is the closure of a circuit for the relay 132, which circuit may be traced as follows: 110 ground at G^{17} , armature 146 and its working contact, contact 156, spring 149, and winding of relay 132 to battery B^{13} . Upon energizing, relay 132 locks from ground on conductor 155 by way of its armature 148. 115 At its upper armature relay 132 prepares a short-circuiting path for relay 130 which, however, is temporarily held open at the upper armature 147 of relay 131.

Returning now to Fig. 4, when the relay 120 225 was energized as a result of the operation of the starting button S , it closed at its lower armature a circuit for the starting magnet 229 of the impulse sender. Upon energizing, the starting magnet 229 closes 125 the contact springs 240 which are locked mechanically in closed position. A circuit is thereby completed for relay 226 which relay, upon energizing, closes at its upper armature a locking circuit for relay 225, and 130

at its lower armature opens the energizing circuit of magnet 229. At the same time the lamp signal L² is lighted in parallel with relay 226. A further result of the closure of springs 230 is the completion of the operating circuit of the motor 233 which now begins to rotate the wheel 231 and the impulse cam 237, the gearing for driving the latter not being shown. The gears are so proportioned that the cam 237 separates the impulse springs 236 once for each lever (not shown) on the wheel 231 which passes the springs 232. As soon as the first displaced lever arrives at the springs 232 the said springs are closed momentarily, thereby completing a circuit for the relay 234. Relay 234 closes in turn a circuit for the magnet 235 which operates to bring a pawl into engagement with the impulse cam, thereby stopping for a brief interval the operation of the motor. As soon as the relay 234 and the magnet 235 retract their armatures (they are made slow-acting by means of copper slugs on their cores) the motor again starts to revolve and another series of impulses is transmitted by the cam 237, the number of impulses being determined as before by the displaced lever on the wheel 231. It will be clear, therefore, that the impulse sender will operate to transmit in this manner as many series of impulses as there were digit keys depressed, the number of impulses in each series being determined by the displaced levers on wheel 231, which levers it will be remembered correspond to the digit keys which were depressed.

Proceeding now to the operation of the automatic switches, the first series of impulses transmitted by the operator's impulse sender serves to effect the setting of the selector E, the operation being controlled over the previously described controlling circuit of the line relay 300. At each interruption of its circuit the line relay 300 is de-energized momentarily and sends an impulse from ground G⁷ to the slow-acting relay 303 and the vertical magnet 304 in series. The vertical magnet, in response to these impulses, operates to step up the switch shaft until the wipers 320, 321, and 322 arrive at the horizontal level of bank contacts in which are located the terminals of trunks extending to the desired connector group.

The relay 303 is energized in series with the vertical magnet and being slow-acting retains its armature during the series of impulses. Upon the first upward movement of the shaft the off-normal springs 311 are closed, thereby completing a circuit for the relay 305 which extends from ground G⁸ by way of the armature and working contact of relay 303 and the said off-normal springs to relay 305. Upon energizing, the relay 305 locks itself independent of relay 65 303 at its upper armature and at its lower armature prepares a circuit for the rotary magnet 306 which is held open during the vertical operation of the switch by the relay 303. At this point it should be mentioned that by the closure of the off-normal springs 311 the line switching relay 302 was connected in series with the relay 305. The junction point 312, however, has already been connected to ground G⁸ as previously described so that the relay 302 is short-circuited and remains inoperative. When the slow-acting relay 303 de-energizes at the end of the series of impulses it completes at its back contact the previously mentioned circuit of the rotary magnet 306, extending from ground G⁸. Upon energizing, the rotary magnet operates to rotate the wipers 320, 321, and 322 into engagement with the first set of bank contacts of the horizontal level opposite which they were raised. Near the end of its stroke the rotary magnet also breaks, at its upper armature, the locking circuit of relay 305; and at its lower armature the circuit of the line switching relay 302. Upon de-energizing, the relay 305 breaks the energizing circuit of the rotary magnet which accordingly retracts its armature to again close its upper and lower contacts. The operation now depends on whether the first trunk line, the terminals of which are now engaged by the selector wipers, is busy or not. Assuming that this trunk line is busy the test contact upon which the test or private wiper 321 is resting will have ground potential upon it, which ground potential will serve to maintain the switching relay 302 short-circuited and also to energize again the relay 305. The rotary magnet circuit is therefore again completed and the same operation is repeated. It will be seen then that the relay 305 will operate as an interrupter to step the switch wipers around through the medium of the rotary magnet as long as the test wiper 321 engages busy or grounded test contacts. When a non-busy or ungrounded contact is reached and the rotary magnet retracts its armature, the junction point 312 will no longer be grounded via the private wiper, whereupon the switching relay 302 will immediately energize in series with the relay 305. Relay 302 is of such high resistance that relay 305 remains inoperative. By the attraction of its armature, the switching relay opens the circuit of the release magnet to provide against the de-energization of relays 300 and 301, shifts the private wiper from its normal connection to junction point 312 to the holding conductor 155, and disconnects the line conductors 153 and 154 from the line relay 300 and extends them by way of the line wipers 320 and 322, bank

contacts 323 and 325, and conductors 370 and 372 to the double-wound relay 350 of the connector F.

The line relay 350 is accordingly energized over the previously described controlling circuit extending back to the operator's impulse sender and upon attracting its armature, completes a circuit for the slow-acting release relay 351. Upon energizing 5 in turn, the relay 351 prepares a circuit for the vertical and rotary magnets 359 and 360 in the usual manner and also completes a new holding circuit which may be traced as follows: ground G²¹, contact and armature 10 of relay 351, conductor 371, bank contact 324, private wiper 321, upper armature and working contact of relay 302 to wire junction 313, where the circuit divides, one branch extending by way of the winding of 15 relay 302, off-normal contact 311, and the winding of relay 305 to the ungrounded pole of battery, and the other branch being the previously traced holding circuit extending 20 back to the primary and secondary finder switches C and D. It is understood 25 that the above described holding circuit is completed before the slow-acting relay 301 of the selector E has had time to deenergize.

After the expiration of a brief interval 30 the second series of impulses will begin coming in over the controlling circuit. Responsive to these interruptions the line relay 350 deenergizes a corresponding number of 35 times and sends each time an impulse from ground at G²² to the slow-acting relay 354 and the vertical magnet 359 in series, side switch wiper 362 being in its first position. The vertical magnet, in response to these 40 impulses, steps up the shaft until the wipers 380, 381, and 382 stand opposite the horizontal level of bank contacts in which the line of substation A² terminates. Relay 354, being slow-acting, retains its armature during the series of impulses and maintains 45 a circuit from ground at G²³ for the private magnet 357 and the wiper cut-off relay 358 in parallel. At the end of the series of impulses, the relay 354 deenergizes and breaks the circuit of the private magnet, which latter 50 controls the side switch wipers in the usual manner to advance them to their second position.

After another brief interval the third and final series of impulses will come in over the 55 controlling circuit, resulting as before in deenergizations of the line relay 350. Now, however, side switch wiper 362 being in its second position, the line relay sends impulses to the slow-acting relay 354 in series 60 with the rotary magnet 360. The rotary magnet operates in response to these impulses to rotate the wipers 380, 381, and 382 until they rest, respectively, upon bank contacts 383, 384, and 385, these contacts forming

the terminal of the line of substation 65 A² in the bank of connector F. The private magnet 357 and the wiper cut-off relay 358 are energized during the series of impulses as before, the latter disconnecting the line wipers during rotation and the former, upon deenergizing, controlling the side switch wipers to advance them to their third position, it being assumed that the line of substation A² was idle when called.

As side switch wiper 363 comes into engagement with its third position contact point, a circuit is completed for the cut-off relay 414 of the called line as follows: ground at G²⁴, side switch wiper 363 (in third position), wiper 381, bank contact 384, 70 and winding of relay 414 to battery B¹⁵. By the closure of the above circuit the cut-off relay 414 is operated to clear the line conductors 412 and 413 from their normal ground and battery connections. Ground at 75 G²⁴ also extends to multiples of bank contact 384 in the banks of other connectors of the group, thereby making the line of substation A² busy to other calls.

By the engagement of side switch wipers 80 364 and 365 with their third position contact points the connection between the calling and called substations is completed, relay 358 being deenergized. By the engagement of side switch wiper 362 with its third 85 position contact point, a circuit is completed for the ringing relay 356 in series with the interrupter I, whereby ringing current is projected intermittently out over the line of substation A² to operate the signal in bridge 90 thereof.

Returning now to the operator's impulse sender (Fig. 4), after the transmission of the last series of impulses, the motor 233 continues to run until the wheel 231 has 105 made a complete revolution and returned to its starting point. Upon the return to normal the springs 230 are unlocked and allowed to separate, thereby stopping the motor 233, deenergizing relay 226, and extinguishing the lamp L². Relay 226, by retracting its armature, breaks the locking circuit of relay 225, which relay deenergizes 110 in turn to remove ground G¹⁵ from conductor 215. One result of this operation is the 115 deenergization of relay 206, which results in the opening of the circuit of relay 207 and the removal of ground from the holding circuit of the primary and secondary line switches M and N, this latter operation resulting 120 in the deenergization of the line switching relays in these line switches. A further result of the removal of ground from conductor 215 is the deenergization of relay 131 of the relay group II. Upon deenergizing, relay 131 completes at its upper armature 147 a short circuit around relay 130, whereupon the said relay 130 also deener-

gizes. It follows then that the line conductors 120 and 121 are again connected, respectively, with the line conductors 133 and 134 as they were originally, except that now by virtue of their temporary extension to the operator's position, the conductors 133 and 134 have been extended into connection with the called line.

It will be seen, therefore, that the required connection between substation A and substation A' has been established and the bell at the latter substation is being rung to attract the attention of the called subscriber. When the called subscriber removes his receiver from the hook a circuit is completed for the double-wound back bridge relay 352 in the well known manner. Upon attracting its armature, relay 352 closes a circuit for the ring cut-off relay 353, which 20 relay looks itself to ground at G³ and also opens the circuit of the ringing relay 355, thereby stopping the ringing operation. As a further result of the energization of relay 352 the incoming line conductors are reversed as regards their connection with the windings of line relay 359. The latter operation is without importance in the system shown here, although it is provided in case it is desired to operate meters or similar apparatus.

The calling and called subscribers may now converse without further effort. Current for the transmitter at substation A is supplied through the windings of the line relay 359, while current for the transmitter at substation A' is supplied through the windings of the back bridge relay 352. The voice currents follow the path shown in the heavy lines which, it is thought, will be apparent without further amplifying the explanation.

When the conversation is finished both subscribers will hang up their receivers. By the replacement of the receiver at substation A, the circuit of the line relay 350 of the connector F is broken. Upon deenergizing, the line relay opens the circuit of slow-acting release relay 351. Upon deenergizing, relay 350 closes a circuit for the release magnet 361, not 361, whereupon the connector F is restored in the usual manner, the circuit of the release magnet 361 being broken at the lower set of off-normal springs when the shaft returns to normal. A further result of the deenergization of relay 351 is the removal of ground G³ from the holding circuit over which the following relays have been maintained energized:—line switching relay 302 of selector E, relay 132 of relay group II, 50 line switching relay 75 of the primary finder switch C, line switching relay 50 of the secondary finder switch D, and the cut-off relay 14. All these relays are accordingly deenergized. By the deenergization of the line switching relay 302 of the selector E, the

said selector is restored through the medium of its release magnet 307 in the same manner as was the connector F. The finder switches, having no normal position, have no releasing operation, the line circuit being broken by the deenergization of the line switching relays. All the apparatus has now been restored to idle condition in readiness for another call.

The operation of a connector switch such as the connector F when connection is attempted with a busy line is well known and has been fully described in the publications previously referred to. Since my invention involves nothing new in connection with this feature of the operation, the description thereof will be omitted.

Having described fully the operations by which the subscriber at the manual substation A obtains connection with another subscriber, it will be unnecessary to discuss, except in a very brief manner, the operation when the calling subscriber is provided with an automatic substation. Assuming that the subscriber at substation A' desires to obtain connection with the subscriber at substation A², he will remove his receiver as usual, thereby initiating the operation of a primary and a secondary finder switch, (the ones shown in Fig. 1 if they are idle), whereupon these switches operate to extend the calling line to the selector switch E in exactly the same manner as has been previously described. In the present case, however, since the terminals 21' and 25' are not connected by a resistance, the current flow in the holding circuit is not sufficient to energize the relay 130 of the relay group II, and the calling line is not trunked to an operator's position. Instead the calling subscriber manipulates his calling device in accordance with the digits in the telephone number of substation A², thereby operating the automatic switches to establish the connection. It is understood that the switches respond to the interruptions produced by the calling subscriber's calling device in exactly the same way as has been previously described with reference to the operator's impulse sender, so that it is thought to be unnecessary to go into further details.

Having described and illustrated my invention, what I consider to be new and desire to have protected by Letters Patent will be pointed out in the appended claims.

What I claim as my invention is:

1. In a telephone system, a plurality of subscribers' lines, a plurality of primary and secondary finder switches for extending said lines when calling, a switching relay in each finder, means for simultaneously starting a primary and secondary finder responsive to a call, and means for thereafter simultaneously energizing the associated switching relays.

2. In a telephone system, a plurality of subscribers' lines, a plurality of primary and secondary finder switches for extending said lines when calling, starting circuits for each of said switches, means common to said primary finder switches for controlling said secondary finder switches and means common to said secondary finder switches for controlling said primary finder switches.
- 10 3. In a telephone system, subscribers' lines divided into groups, a plurality of line finder switches for each group for extending calling lines therein, a plurality of trunk finder switches for further extending lines in any group, a relay for each group of lines, a circuit controlled by each relay for starting an idle line finder, and a circuit controlled by said relays in common for starting an idle trunk finder.
- 15 4. In a telephone system, a plurality of subscribers' lines, a plurality of primary and secondary finder switches for extending said lines when calling, fixed and movable terminals in said finder switches for completing such extensions, each movable terminal being at all times in engagement with one of said fixed terminals, and means responsive to the initiation of a call for starting a primary and secondary finder simultaneously.
- 20 5. In a telephone system, a subscriber's line, trunk lines, a progressively movable trunking switch for extending a connection from said subscriber's line to any one of said trunk lines, an individual line relay for said line at the exchange, means for partially operating said relay when the said line is calling, and means for completely energizing said relay when the said line is called.
- 25 6. In a telephone system, a subscriber's line, an individual line relay for said line at the exchange, said relay operable in two stages, a trunking switch for extending said line when calling, a circuit including said line for operating said relay through its first stage to provide for the extension of said line via said switch, and a second circuit completed after said switch has operated for operating said relay through its second stage to open said first circuit.
- 30 7. In a telephone system, a subscriber's line, a trunking switch for extending said line when calling, a circuit including said line for initiating the operation of said switch, a relay individual to said line and having a winding in said circuit, contacts on said relay for opening said circuit, and means controlled by said switch for operating said relay.
- 35 8. In a telephone system, manual and automatic subscribers' lines, automatic switches at the exchange for connecting calling and called lines of either kind, means for extending any calling line to one of said switches, an operator's position, and means whereby the said calling line, if a manual line, is then automatically extended to the operator's position.
- 40 9. In a telephone system, manual and automatic subscribers' lines, an operator's position, means for connecting a calling line with said operator's position, and controlling means for said connecting means, said controlling means adapted to discriminate between manual and automatic calling lines, whereby the former only are so extended.
- 45 10. In a telephone system, manual and automatic subscribers' lines, an operator's position at the exchange, trunk lines, means for connecting calling lines of either kind with idle trunk lines, an automatic trunking switch for each trunk line, and means in each trunk line responsive only to the connection of a manual calling line thereto for extending such trunk line to its associated automatic switch.
- 50 11. In a telephone system, a trunk line having two branches, circuits of two different kinds, means for connecting any circuit with said trunk line, and discriminating switching means in said trunk line, whereby one kind of circuit is extended via one of said branches and the other kind of circuit is extended via the other of said branches.
- 55 12. In a telephone system, subscribers' lines of two kinds, an automatic switch, means for connecting any line when calling with said switch, a trunk line, and means actuated only when the calling line is of a particular kind for switching such calling line from connection with said switch into connection with said trunk line.
- 60 13. In a telephone system, subscribers' lines of two kinds, an automatic switch, means for connecting any line when calling with said switch, a trunk line, means actuated only when the calling line is of a particular kind for switching such calling line from connection with said switch into connection with said trunk line, and an operator's position in which said trunk line terminates.
- 65 14. In a telephone system, subscribers' lines of two kinds, an automatic switch, means for connecting any line when calling with said switch, a trunk line, means actuated only when the calling line is of a particular kind for switching such calling line from connection with said switch into connection with said trunk line, an operator's position in which said trunk line terminates, an impulse transmitter, means for connecting it with said trunk line, and means for switching said trunk line from connection with said calling line into connection with said switch, whereby said switch may be controlled by said transmitter.
- 70 15. In a telephone system, subscribers' lines of two kinds, an automatic switch, means for connecting any line when calling

with said switch, a trunk line, means actuated only when the calling line is of a particular kind for switching such calling line from connection with said switch into connection with said trunk line, an operator's position in which said trunk line terminates, an impulse transmitter, means for connecting it with said trunk line, means for switching said trunk line from connection with 10 said calling line into connection with said switch, whereby said switch may be controlled by said transmitter, and means for rendering said switching means ineffective whereby the said calling line is again connected to said switch.

16. In a telephone system, manual and automatic subscribers' lines, means including a plurality of directly controlled automatic switches for connecting calling 20 and called lines of either kind, an operator's equipment and means associated therewith for controlling said switches, means for connecting any calling line to a first one of said switches, automatic means responsive only 25 to manual lines for then switching the calling line to said equipment, means for then connecting said equipment with said first switch, and means effective after said switch has been operated for again connecting the 30 calling line thereto.

17. In a telephone system, a plurality of subscribers' lines, a plurality of primary and secondary finder switches for extending said lines when calling, a switching relay in each 35 finder, means for starting a primary and secondary finder responsive to a call, and means for thereafter simultaneously energizing the associated switching relays.

18. In a telephone system, subscribers' 40 lines, a directly controlled switch, line finder switches and a trunk finder switch for extending a calling line to said directly controlled switch, a relay in said trunk finder switch for completing such extension, 45 and means common to said line finder switches for controlling the operation of said relay.

19. In a telephone system, subscribers' 50 lines, a directly controlled switch, line finder switches and a trunk finder switch for extending a calling line to said directly controlled switch, a relay in said trunk finder switch for completing such extension, a circuit for said relay, and means common to 55 said line finder switches actuated in the operation thereof to prevent the closure of said circuit.

20. In a telephone system, subscribers' 60 lines divided into groups, a plurality of line finder switches for each group for extending calling lines therein, a plurality of trunk finder switches for further extending lines in any group, a relay individual to each group of lines, a circuit controlled by each 65 relay for starting an idle line finder in the

group to which the relay is individual, and a circuit controlled by said relays in common for starting an idle trunk finder.

21. In a telephone system, a plurality of subscribers' lines, a plurality of trunk lines, a plurality of primary and secondary finder switches for extending said lines to split trunk lines when calling, fixed and movable terminals in said finder switches for completing such extensions, each movable terminal being at all times in engagement with, one of said fixed terminals, and means responsive to the initiation of a call for starting a primary and secondary finder simultaneously.

22. In a telephone system, a trunk line having a normally open branch, circuits of different electrical character, means for connecting any circuit with said trunk line, and switching means dependent on the electrical characteristics of a connected circuit for closing said branch.

23. In a telephone system, a calling and a called line, means including an automatic switch for connecting said lines, means for extending the calling line to said switch, a trunk to an operator's position, intermediate means for switching the calling line from a connection with said switch into connection with said trunk, a call sender at the operator's position, and means for connecting said sender with said switch to operate the same, said switching means operating in accordance with the character of the calling line.

24. In a telephone system, calling lines and 100 called lines, said calling lines having different characteristics, means including an automatic switch for connecting said lines, means for extending the calling line to said switch, a trunk to an operator's position, and 105 automatic means for switching the calling lines from connection with said switch into connection with said trunk when only certain of said lines are connected, a call sender at the operator's position, means for connecting the said sender with said switch to operate the same, and automatic means for thereafter disabling said switching means, whereby the said calling line is again connected with said switch.

25. In a telephone system, subscribers' 110 lines, a trunk line extending to an operator's position, means for connecting a calling line with said trunk line, means associated with certain of said lines for breaking about the 120 operation of said connecting means, and means associated with certain other of said lines for preventing the operation of said connecting means.

26. In a telephone system, subscribers' 125 lines, a trunk line provided with directly controlled selecting mechanism and automatic selecting mechanism, either of said mechanisms being operable independent of the operation of the other, means for extend-

ing a calling line to said trunk, and means associated with the calling line for initiating the operation of said automatic selecting mechanism.

- 5 27. In a telephone system, subscribers' lines, a trunk line provided with selecting mechanism, other trunk lines in groups, an automatic switch for extending a calling line to said first trunk line, means whereby the 10 calling subscriber may control a portion of said mechanism to select a desired one of said groups of trunk lines, another group of trunk lines, automatic means for controlling another portion of said mechanism to select 15 a trunk in said other group, and means individual to the calling line for initiating the operation of said automatic means.

28. In a telephone system, a plurality of subscribers' lines, a plurality of primary and 20 secondary finder switches for extending said lines when calling, a switching relay in each finder, a relay for simultaneously starting a primary and secondary finder responsive to a call, and means for thereafter simultaneously energizing the associated switching 25 relays.

29. In a telephone system, a plurality of subscribers' lines, a plurality of primary and secondary finder switches for extending said 30 lines when calling, starting circuits for each of said switches, a relay common to said primary finder switches for controlling said secondary finder switches and a relay common to said secondary finder switches for 35 controlling said primary finder switches.

30. In a telephone system, a plurality of subscribers' lines, a plurality of line finder switches controlled from said lines for finding any one of said lines, a plurality of 40 trunk finder switches for finding any one of said line finders, said trunk finders controlled also from said lines, whereby a connection may be established from any one of said lines to one of said line finders and 45 through one of said trunk finders to another line.

31. In a telephone system, a plurality of lines, a relay common to said lines, a plurality of line finders, a plurality of trunk finders, said relay controlled from said lines, said line and trunk finders controlled by said relay, the line finders to find the lines and the trunk finders to find the line finders.

32. In a telephone system, a plurality of 55 subscribers' lines, a plurality of line finder switches controlled from any one of said lines for finding any one of said lines, a plurality of trunk finder switches for finding any one of said line finders, said trunk finders controlled also from any one of said lines, whereby a connection may be established from any one of said lines to one of said line finders and through one of said trunk finders to another line.

65 33. In a telephone system, a plurality of

lines, a relay common to said lines, a plurality of line finders, a plurality of trunk finders, said relay controlled from any one of said lines, said line and trunk finders controlled by said relay, the line finders to find the lines and the trunk finders to find the line finders.

34. In a telephone system, a plurality of subscribers' lines, a plurality of primary and secondary finder switches for extending said lines when calling, a switching relay in each finder, a relay for simultaneously starting a primary and secondary finder responsive to a call, means for thereafter simultaneously energizing the associated switching relays, each finder having a wiper and a bank with a line terminal for each line with means for moving said wiper into engagement with any one of said terminals to find a line, each of said trunk finders having a wiper and a bank of terminals one for each line finder, and means for moving its wiper into engagement with any one of the line finder terminals to make the connection with a line finder.

35. In a telephone system, a plurality of subscribers' lines, a plurality of primary and secondary finder switches for extending said lines when calling, starting circuits for each of said switches, a relay common to said primary finder switches for controlling said secondary finder switches and a relay common to said secondary finder switches for controlling said primary finder switches, each finder having a wiper and a bank with a line terminal for each line with means for moving said wiper into engagement with any one of said terminals to find a line, each of said trunk finders having a wiper and a bank of terminals one for each line finder, and means for moving its wiper into engagement with any one of the line finder terminals to make the connection with a line finder.

36. In a telephone system, manual and 110 automatic subscribers' lines, automatic switches at the exchange for connecting calling and called lines of either kind, subscriber controlled means for extending any calling line to one of said switches, an operator's position, and electromagnetic means whereby the said calling line, if a manual line, is then automatically extended to the operator's position.

37. In a telephone system, manual and 120 automatic subscriber's lines, an operator's position at the exchange, trunk lines, means for connecting calling lines of either kind with idle trunk lines, an automatic trunking switch for each trunk line, and a relay in 125 each trunk line responsive only to the connection of a manual calling line thereto for extending such trunk line to its associated automatic switch.

38. In a telephone system, manual and au-

- tomatic subscribers' lines, an operator's position, automatic switching mechanism common to a plurality of said subscribers' lines for connecting a calling line with said operator's position, a relay for controlling said switching mechanism, said relay adapted to be operated when the calling line is a manual line, and inoperative when the calling line is an automatic line, whereby the former 5 only are extended to said operator's position.
39. In a telephone system, a subscriber's line, a trunking switch for extending said line when calling, a circuit including said line for initiating the operation of said 10 switch, a relay individual to said line, a winding of said relay included in said line circuit whereby said relay may be energized thereover, contacts on said relay for controlling a plurality of circuits, one of said 15 circuits being the said line circuit, an energizing circuit for said relay controlled by said switch, said relay operating to open the said line circuit when energized by said switch.
40. In a telephone system, manual and automatic subscribers' lines, an operator's position, means for connecting one of said lines with said operator's position, and controlling means for said connecting means, said controlling means having a relay responsive 20 only to the manual line equipment, whereby said connecting means is operated to connect only manual lines to the operator's position.
41. In a telephone system, manual and automatic subscribers' lines, an operator's position at the exchange, trunk lines, means for connecting calling lines of either kind with idle trunk lines, an automatic trunking switch for each trunk line, and means in each trunk line responsive only to the 25 equipment of a manual calling line for extending such trunk line to its associated automatic switch, thereby discriminating against the automatic lines.
42. In a telephone system, a trunk line having two branches, calling circuits of two different kinds, means for connecting any one of said circuits with said trunk line, and automatic discriminating switching means in said trunk line, whereby one kind of circuit is extended via one of said branches and the other kind of circuit is extended via the other of said branches.
43. In a telephone system, subscribers' lines of two kinds, an automatic switch, 30 means for connecting any one of said lines when calling with said switch, a trunk line, and automatic means actuated only when the calling line is a particular kind for

switching such calling line from connection with said switch into connection with said 35 trunk line.

44. In a telephone system, subscribers' lines of two kinds, an automatic switch, means for connecting any one of said lines when calling with said switch, a trunk line, 40 automatic means actuated only when the calling line is of a particular kind for switching such calling line from connection with said switch into connection with said trunk line, and an operator's position in 45 which said trunk line terminates.

45. In a telephone system, subscribers' lines of two kinds, an automatic switch, means for connecting any one of said lines when calling with said switch, a trunk line, 50 automatic means actuated only when the calling line is of a particular kind for switching such calling line from connection with said switch into connection with said trunk line, an operator's position in which 55 said trunk line terminates, an impulse transmitter, means for connecting it with said trunk line, and means for switching said trunk line from connection with said calling line into connection with said switch, whereby 60 said switch may be controlled by said transmitter.

46. In a telephone system, subscribers' lines of two kinds, an automatic switch, means for connecting any one of said lines 65 when calling with said switch, a trunk line, automatic means actuated only when the calling line is of a particular kind for switching such calling line from connection with said switch into connection with said 70 trunk line, an operator's position in which said trunk line terminates, an impulse transmitter, means for connecting it with said trunk line, means for switching said trunk line from connection with said calling line 75 into connection with said switch, whereby said switch may be controlled by said transmitter, and means for rendering said switching means ineffective whereby the said calling line is again connected to said switch.

47. In a telephone system, a trunk line having a normally open branch, circuits of different electrical character, means for connecting any one of said circuits with said trunk line, and automatic switching means 80 dependent on the electrical characteristics of a connected circuit for closing said branch.

Signed by me at Chicago, Cook county, State of Illinois, this 15th day of July, 1916. 85
WINFRED T. POWELL.

DISCLAIMER.

1,308,553.—*Winfred T. Powell*, Chicago, Ill. TELEPHONE-EXCHANGE SYSTEM. Patent dated July 1, 1919. Disclaimer filed April 15, 1927, by the assignee by mesne assignments, *Automatic Electric Inc.*

Hereby enters a disclaimer to claims 8, 9, 22, 25, 26, 36, 38, 40, and 47 in said specification, which are in the following words, to wit:

“8. In a telephone system, manual and automatic subscribers' lines, automatic switches at the exchange for connecting calling and called lines of either kind, means for extending any calling line to one of said switches, an operator's position, and means whereby the said calling line, if a manual line, is then automatically extended to the operator's position.

“9. In a telephone system, manual and automatic subscribers' lines, an operator's position, means for connecting a calling line with said operator's position, and controlling means for said connecting means, said controlling means adapted to discriminate between manual and automatic calling lines, whereby the former only are so extended.

“22. In a telephone system, a trunk line having a normally open branch, circuits of different electrical character, means for connecting any circuit with said trunk line, and switching means dependent on the electrical characteristics of a connected circuit for closing said branch.

“25. In a telephone system, subscribers' lines, a trunk line extending to an operator's position, means for connecting a calling line with said trunk line, means associated with certain of said lines for bringing about the operation of said connecting means, and means associated with certain other of said lines for preventing the operation of said connecting means.

“26. In a telephone system, subscribers' lines, a trunk line provided with directly controlled selecting mechanism and automatic selecting mechanism, either of said mechanisms being operable independent of the operation of the other, means for extending a calling line to said trunk, and means associated with the calling line for initiating the operation of said automatic selecting mechanism.

“36. In a telephone system, manual and automatic subscribers' lines, automatic switches at the exchange for connecting calling and called lines of either kind, subscriber controlled means for extending any calling line to one of said switches, an operator's position, and electromagnetic means whereby the said calling line, if a manual line, is then automatically extended to the operator's position.

“38. In a telephone system, manual and automatic subscribers' lines, an operator's position, automatic switching mechanism common to a plurality of said subscribers' lines for connecting a calling line with said operator's position, a relay for controlling said switching mechanism, said relay adapted to be operated when the calling line is a manual line, and inoperative when the calling line is an automatic line, whereby the former only are extended to said operator's position.

“40. In a telephone system, manual and automatic subscribers' lines, an operator's position, means for connecting one of said lines with said operator's position, and controlling means for said connecting means, said controlling means having a relay responsive to the manual line equipment, whereby said connecting means is operated to connect only manual lines to the operator's position.

“47. In a telephone system, a trunk line having a normally open branch, circuits of different electrical character, means for connecting any one of said circuits with said trunk line, and automatic switching means dependent on the electrical characteristics of a connected circuit for closing said branch.
